(57) **CLAIM**

The ornamental design for a ground fault circuit interrupter, as shown and described.

DESCRIPTION

FIG. 1 is a right front perspective side view of a ground fault circuit interrupter according to a first embodiment of the present invention;

FIG. 2 is a right back perspective view of a ground fault circuit interrupter according to a first embodiment of the present invention;

FIG. 3 is a front view of a ground fault circuit interrupter according to a first embodiment of the present invention;

FIG. 4 is a back view of a ground fault circuit interrupter according to a first embodiment of the present invention;

FIG. 5 is a left side view of a ground fault circuit interrupter according to a first embodiment of the present invention;

FIG. 6 is a right side view of a ground fault circuit interrupter according to a first embodiment of the present invention;

FIG. 7 is a top view of a ground fault circuit interrupter according to a first embodiment of the present invention; and

FIG. 8 is a bottom view of a ground fault circuit interrupter according to a first embodiment of the present invention;

FIG. 9 is a right front perspective view of a ground fault circuit interrupter according to a second embodiment of the present invention;

FIG. 10 is a right back perspective view of a ground fault circuit interrupter according to a second embodiment of the present invention;

FIG. 11 is a front view of a ground fault circuit interrupter according to a second embodiment of the present invention;

FIG. 12 is a back view of a ground fault circuit interrupter according to a second embodiment of the present invention;

FIG. 13 is a left side view of a ground fault circuit interrupter according to a second embodiment of the present invention;

FIG. 14 is a right side view of a ground fault circuit interrupter according to a second embodiment of the present invention;

FIG. 15 is a top view of a ground fault circuit interrupter according to a second embodiment of the present invention; and

FIG. 16 is a bottom view of a ground fault circuit interrupter according to a second embodiment of the present invention;

In the drawings, the broken lines depict unclaimed subject matter only and form no part of the claimed design.
